[57] CLAIM

The ornamental design for a bracket for holding fishing rods or the like, as shown.

DESCRIPTION

FIG. 1 is a front elevation view of a bracket for holding fishing rods or the like showing my new design;
FIG. 2 is a top plan view thereof;
FIG. 3 is a bottom plan view thereof;
FIG. 4 is a left side elevation view thereof; and
FIG. 5 is a right side elevation view thereof.
